Assistant Examiner—Robert Spear
Attorney, Agent, or Firm—Browning Bushman**[57] CLAIM**

The ornamental design for a trailer chain holder, as shown and described.

DESCRIPTION

FIG. 1 is a rear left perspective view of the trailer chain holder according to the present invention, with a portion of a rear vehicle bumper and a portion of a chain illustrated in dashed lines and forming no part of the claimed design; FIG. 2 is an enlarged front view of the trailer chain holder as shown in FIG. 1;

FIG. 3 is an enlarged rear view of the trailer chain holder as shown in FIG. 1;

FIG. 4 is an enlarged side view of the trailer chain holder where the opposite side view is a mirror image thereof;

FIG. 5 is an enlarged bottom end view of the trailer chain holder as shown in FIG. 1; and,

FIG. 6 is an enlarged top end view of the trailer chain holder as shown in FIG. 1.
